UNITED STATES PATENT OFFICE.

DONALD MACGREGOR, OF PORTLAND, OREGON, ASSIGNOR OF ONE-HALF TO JOHN BOYD, OF PORTLAND, OREGON.

BORING DEVICE.

1,080,356.

Specification of Letters Patent.

Patented Dec. 2, 1913.

Application filed December 20, 1912. Serial No. 737,794.

To all whom it may concern:

Be it known that I, DONALD MACGREGOR, a citizen of the United States, residing in the city of Portland, county of Multnomah, 5 and State of Oregon, have invented certain new and useful Improvements in Boring Devices, of which the following is a specification.

My invention relates to boring devices, 10 and more particularly to a power-driven boring device designed and adapted especially for boring through, or into, the stump of a tree for the purpose of making a hole in which a fire can be started, or into which a 15 charge of explosive can be inserted for the purpose of burning or blowing out said stump.

Among the salient objects of my invention are, to provide a simple, practicable 20 and successful, power-actuated boring device, capable of being easily transported from place to place and having a capacity which adapts it for boring holes through all sizes of stumps, no matter how large they 25 may be; to provide a device of the character referred to capable of ready adjustment into various positions or angles for operation; to provide in a device of the character referred to, a feed mechanism for feeding the 30 auger into the stump and by means of which it can be easily, quickly, and repeatedly withdrawn and inserted during its operation for the purpose of discharging the borings or shavings cut thereby.

35 Other objects and improvements will appear from the following description of one embodiment of the invention shown on the accompanying sheet of drawings and forming a part hereof, and in which,

40 Figure 1 is a top plan view thereof; and Fig. 2 is a side elevation thereof.

Referring now to the drawings, 1 and 2 45 designate two supporting standards, which may be mounted upon any suitable base or bed plate, as 3, and each of which is provided with a plurality of bearing sockets, as 4, 5 and 6. Hingedly and interchangeably mounted in corresponding bearing sockets of said standards is what I will call a power 50 frame, composed of two parallel side bars or pipes, 7—8, coupled fixedly together by means of end pieces or castings 9 and 10, with a driving shaft 11 rotatably mounted therethrough, as indicated, and carrying 55 upon its outer end a driving pulley 12, and

upon its inner end a beveled gear 13. Said power frame is hingedly mounted and supported in the bearing sockets of said standards by means of suitable bearing hooks 14—14, which are adapted to pass through 60 said standards 1 and 2, adjacent the bearing sockets in use, with their hooked portions around the side pipe or bar 8, and their opposite ends provided with nuts, 15—15, whereby the hooked portions can be tightened 65 around the pipe 8, as may be desired.

The casting 10, it will be noted, is of L 70 shape, with a portion thereof, designated 10', constituting an end or bearing casting for what I will call a boring frame and which 75 also comprises two parallel bars or pipes 16—17, having their forward ends secured within the part 10' of the casting 10, and having their opposite ends fixedly secured together by means of an end casting, as 18, 75 which said casting 18 is adjustably attached to a slotted standard, 19, by means of a bolt and nut at 20, whereby it can be raised and lowered into different angular positions and there secured by means of said bolt 20. The 80 lower end of said slotted standard 19 is jointed, as at 21, and made adjustable by means of a bolt and nut at 22, said standard being mounted upon the base 3.

Slidably mounted upon the parallel bars 85 or pipes 16—17, is a feed head 23, rotatably mounted in which is the end of a driving shaft 24, here shown to be square in cross section, and extended forwardly through the casting 10', and provided at its forward 90 end with an auger chuck 25, adapted to receive an auger 26. Mounted upon said driving shaft 24 is a beveled gear 27, having an integral sleeve portion 27' within the box or bearing of the casting 10', said beveled gear 27 being positioned to mesh with the gear 13

so as to be driven therefrom, whereby to drive said driving shaft 24 through said gear 27 and its sleeve 27', and at the same 100 time permit said shaft 24 to be moved longitudinally therethrough in either direction. As a means for feeding said shaft 24 forwardly or for withdrawing it rearwardly, a bearing sleeve 28 is mounted upon the feed head 23 to receive a shaft 29, provided at its upper end with a crank 30, and at its lower end with a sprocket wheel 31.

105 Stretched between the end castings 18 and 10', and parallel with the bars or pipes 16—17, is a sprocket chain 32, with means at its 110

- forward end, as at 33, for tightening the same, as may be desired. This sprocket chain is positioned to be engaged by the sprocket wheel 31 so that when the latter is turned in either direction by means of the hand crank 30, the feed head 23 and the driving shaft 24 are moved forwardly or rearwardly, according to the direction in which said crank is turned, thus feeding the auger 26 forwardly, or moving it backwardly, as in withdrawing it from the bore being made to discharge the borings or shavings therefrom. In order to hold the chain against the sprocket and to prevent disengagement, the feed head 23 is provided at its lower side, adjacent the chain and at opposite sides of the sprocket wheel 31, with two downwardly depending lug elements 34—34.
- 20 Any suitable power furnishing mechanism may be used, although I prefer to employ a light gasoline engine of two or three horse power, which can be mounted upon the base at any suitable position for driving the pulley 12. I have shown no form of power mechanism, as this forms no part of the invention.
- 25 By providing the standards 1 and 2 with different bearing sockets, as 4, 5 and 6, the power frame and the forward end of the boring frame may be adjusted to as many different heights. As shown in Fig. 2, said parts are mounted in the lowest position, and the parts are in position for boring into a 30 stump in a straight horizontal line. By means of the slotted standard 19, the rear end of the boring frame can be raised to different heights, thereby giving different angles to the boring shaft 24, thus making it possible to bore directly into and through 35 a stump on a horizontal line, or at most any angle desired.
- 40 It will thus be seen that I have provided a light boring device which can be moved from place to place by two men, and one in which the auger is power actuated, and in which the auger can, during its operation be withdrawn repeatedly to discharge the shavings. This can be accomplished without 45 stopping the engine, thus making it possible to very quickly bore a hole straight through a large stump, or to bore down into one at an angle. The length of the shaft 24 makes it possible to bore through a very large stump, 50 and in case the stump is larger through than the shaft 24 and auger combined, after the auger and shaft have entered the stump for some distance, the supporting base and the whole device can be moved close up, 55 against the stump, thereby gaining the distance from the end of the auger to the boring frame, represented by the auger, the auger chuck and the projecting end of the power shaft 24, as shown in Fig. 2.
- 60 65 I am aware that modifications can be made

in the embodiment of the invention here shown and described without departing from the spirit thereof, and I do not, therefore, limit the invention to this specific form, except as I may be limited by the hereto appended claims.

I claim:

1. A portable boring device for boring stumps of trees, comprising a base, supporting standards mounted thereupon, a power frame with power shaft therein, a boring frame adjustably mounted upon said base, an angular bearing casting rigidly connecting said power frame and said boring frame with each other at right angles, said frames being hingedly connected to said standards, beveled gears in mesh with each other in the angle of said casting and driven from said power shaft, a driving shaft mounted in said boring frame, through one of said gears and movable longitudinally therethrough, said shaft being provided with holding means for an auger at its forward end and with a feed head slidably mounted upon said boring frame at its rearward end, and means for mechanically moving said feed head and said boring shaft longitudinally through said boring frame and beveled gear, substantially as shown and described. 85

2. A boring device of the character referred to comprising in combination, a supporting base, supporting standards mounted thereupon, a power frame adjustably mounted upon said standards and provided with power shaft having a driving pulley and a gear, a boring frame connected at its forward end, at right angles, to said power frame, and provided with a driving shaft rotatably mounted therein and adapted to be adjusted longitudinally therethrough, an auger carried by the forward end of said driving shaft, a driving gear meshing with said first gear and through which said driving shaft has a driving and sliding connection, and a feed mechanism connected at the rear end of said driving shaft in said boring frame, whereby to move said shaft longitudinally in either direction during the boring operation. 100 110 105

3. In a boring device of the character referred to, in combination, a supporting base, supporting standards mounted thereupon, a power frame adjustably and pivotally mounted on said standards and provided with a power shaft having a driving pulley and a beveled gear at its opposite ends; a boring frame connected at its forward end and at an angle thereto with said power frame, and provided with a driving shaft rotatably and slidably mounted therein, and provided at its forward end with an auger, a beveled gear having a bearing in said frame and meshing with said first mentioned beveled gear, to be driven therefrom, said driving shaft having a driving and sliding 115 120 125 130

connection therethrough, whereby to be driven by said gear, said boring frame being vertically adjustable at its rear end, a supporting standard for the rear end of said 5 boring frame and feed mechanism connected at the rear end of said driving shaft for moving it longitudinally, for the purpose mentioned.

4. A boring device, comprising in combination, a supporting base, supporting vertical standards mounted thereupon, a power frame adjustably and hingedly mounted on said standards and provided with a power shaft having a driving pulley and a beveled 10 gear, a boring frame comprising parallel shafts secured together at their opposite ends and rigidly connected at their forward ends, at an angle to said power frame, and provided with a driving shaft rotatably and 15 slidably mounted therein, and provided at its forward end with an auger, a feed head slidably mounted upon said parallel shafts 20

and secured to the rear end of said driving shaft, a beveled driving gear upon said driving shaft and meshing with said first gear, 25 whereby to be driven thereby, a sprocket chain secured at its opposite ends to the opposite ends of said boring frame, a sprocket wheel rotatably mounted upon said feed head, movable therewith and meshing 30 with said sprocket chain, whereby to positively move said feed head and driving shaft longitudinally in either direction, with means for operating said sprocket wheel, and means for adjusting said boring frame 35 and driving shaft vertically into different angular positions, substantially as described.

Signed at Portland, Oregon, December 13th, 1912.

DONALD MacGREGOR.
